UNITED STATES PATENT OFFICE

RALPH H. GOLDMAN, OF NEW YORK, N. Y., ASSIGNOR TO HENRY L. HUGHES CO., INC.,
OF NEW YORK, N. Y., A CORPORATION OF NEW YORK

DESIGN FOR A MANICURE INSTRUMENT

Application filed April 8, 1930. Serial No. 35,189. Term of patent 14 years.

To all whom it may concern:

Be it known that I, RALPH H. GOLDMAN, a citizen of the United States, residing at New York, county of New York, State of New York, have invented a new, original, and ornamental Design for Manicure Instrument, of which the following is a specification, reference being had to the accompanying drawing, forming a part thereof.

Figure 1 is a side elevational view, and
Figure 2 is an edge view.

I claim:

The ornamental design for a manicure instrument substantially as shown.

RALPH H. GOLDMAN.
